UNITED STATES PATENT OFFICE.

DAVID BUSHBY, OF KEDDLESTON, SASKATCHEWAN, CANADA.

CARBON-REMOVING DEVICE.

Application filed April 20, 1921. Serial No. 462,909.

To all whom it may concern:

Be it known that I, DAVID BUSHBY, a subject of the King of Great Britain, residing at Keddleston, in the Province of Saskatchewan and Dominion of Canada, have invented certain new and useful Improvements in Carbon-Removing Devices, of which the following is a specification.

The present invention relates to carbon removing devices applicable to oil, gas, or other internal combustion engines and is particularly adapted to prevent sticking of the valve stem or clogging of the valve on its seat, by carbon deposits.

In oil, gas, and other internal combustion engines there is, necessarily, considerable carbon deposit on and about the exhaust valve stems and valves or valve seats. On the stems this deposit soon forms a heavy gum which causes the valve stems to stick tight in their bores. On the valves and valve seats, its accumulation soon causes imperfect closure of the valve, with consequent leakage. Every time a valve stem sticks, the engine must be stopped and the stem freed, and whenever there is leakage from imperfect valve seating there is loss of power. The main objects of the present invention are to completely avoid these objections by automatically removing all carbon as fast as it is deposited, so that it can not accumulate. This is done automatically, through the operation of the engine. Furthermore, no change of any kind is required in the present structure and no parts are added or inserted which in any degree alter the operation of any existing parts, by actual engagement or cooperation with such parts.

In order to more clearly disclose the construction, operation, and use of the invention, reference should be had to the accompanying drawings forming part of the present application. Throughout the several figures of the drawings, like reference characters designate the same parts in the several views.

In the drawings:

Fig. 1 is a view of the invention as applied horizontally to an oil engine;

Fig. 2 is a fragmentary view of a cylinder section of an engine, showing the valve and valve stem, with the preferred form of the invention applied; and

Fig. 3 is a like view of a modification.

In the drawings, the invention has been illustrated as applied to the valve stem of a

gasoline or similar engine, with the valve operating vertically except in Fig. 2 where it is shown applied to an oil engine, and operating horizontally. It is to be understood that the drawing illustrates only two arrangements and that the device is fully applicable to valves disposed and operating in any direction or position, and, of course, that it is fully applicable with oil, gasoline, and all internal combustion engines in which, during operation, there is an appreciable carbon deposit.

There are various forms in which the device may be made and several ways in which it may be applied and operated. In the drawings, two slightly different constructions are shown. Preferably, the device comprises a ring 1 adapted to fit loosely on the valve stem between the inner end of the valve stem bore and the valve itself. Or, as in Fig. 3, several rings 1' may be used. The slight space between the ring and the stem permits the ring to rattle or hammer against the valve stem, as the stem rapidly reciprocates during the operation of the valve. The reciprocations are both rapid and sudden. The resulting rattling of the ring causes a decided hammering effect on the stem. This imparts a rapid jarring of the stem and its valve at every longitudinal movement of the stem. The result is that all carbon particles, as rapidly as deposited, are immediately jarred from the stem and valve, so that it is kept free and all sticking of the stem or uneven seating of the valve are avoided.

While the device has been illustrated in Fig. 1 as a ring, it is evident that a non-circular link, convolute ring, or other form of element may be equally well used provided that it is loose on the stem and so disposed as to give the same hammering or jarring effect as the ring. Of course, several elements may be used, as in Fig. 3. And likewise, these several elements need not all be alike. One may have one form and another, another form.

Changes may be made in the construction, arrangement and disposition of the several parts of the invention, within the scope of the claims, without in any way departing from the field and scope of the invention, and it is meant to include all such within this application, wherein only preferred forms have been disclosed by way of illustration.

Having thus described my invention, what

I claim and desire to protect by Letters Patent is:

1. In combination with the reciprocating stem of a valve, a member loosely mounted thereon and adapted to jar the same as it reciprocates.
2. In combination with a movable valve stem, means for jarring the same during operation to remove carbon deposit therefrom.
3. In combination with a movable valve stem, means for automatically jarring the same during operation to remove carbon deposit therefrom.
4. In combination with a movable valve stem, means mounted thereon and actuated by the movement thereof to jarr said stem and maintain it free of carbon deposit.
5. In combination with a movable valve stem, means slidably mounted thereon and actuated by the movement thereof to jarr said stem and maintain it free of carbon deposit.
6. In combination with a movable valve stem, a ring loosely mounted thereon and actuated by the movement thereof to strike against and jarr said stem and maintain it free of carbon deposit.
7. A carbon removing device for internal combustion engines comprising, a rapidly reciprocable valve stem, and a member loosely mounted thereon and spaced therefrom, said member being engaged and actuated by said stem as it reciprocates, thereby causing said member to pound rapidly against the stem and jar it to dislodge accumulating carbon.
8. A carbon removing device for internal combustion engines comprising, a rapidly reciprocable valve stem, and a metal ring loosely mounted concentrically thereon and spaced therefrom, said ring being engaged

and actuated by said stem as it reciprocates, thereby causing said member to pound rapidly against the stem and jar it to dislodge accumulating carbon.

9. The combination with an internal combustion engine having a valve provided with a guided stem, of a means for preventing the formation of carbon on the valve stem, consisting of a member loosely mounted on the stem between the valve portion and the stem guide and freely movable laterally and vertically thereon independently of the movement of the valve.

10. The combination with an internal combustion engine having a valve opening and a valve stem guide, a valve closing said opening and having a stem guided in said guide, and a ring-like member loosely mounted on the valve stem between the valve portion and the stem guide and freely movable laterally and vertically thereon independently of the movement of the valve for removing carbon therefrom.

11. The combination with an internal combustion overhead valve engine having an exhaust opening and a valve stem guide, a reciprocal valve controlling said exhaust opening, and a ring-like member loosely mounted on the valve stem between the valve portion and the stem guide and freely movable laterally and vertically thereon independently of the movement of the valve for removing the carbon therefrom.

In testimony whereof, I have signed my name to this specification in the presence of two subscribing witnesses.

DAVID BUSHBY.
